K. O. F. JACOBSEN

SWIMMING SHOE

Filed Sept. 13, 1926

UNITED STATES PATENT OFFICE.

KARL OSCAR FREDRICK JACOBSEN, OF SEATTLE, WASHINGTON.

SWIMMING SHOE.

Application filed September 13, 1926. Serial No. 135,065.

The invention is a device that may be attached to the soles of shoes which will operate to provide a greater bearing surface to assist pedal propulsion.

- 5 The object of the invention is to provide a mechanical device that may be attached to the feet of a swimmer which will automatically operate to multiply the bearing area of the soles of the feet.
- 10 Another object of the invention is to provide a simple and efficient device for increasing the propelling surface of a swimmer's feet.

A further object of the invention is to provide means for attaching a pair of propelling blades to the sole of a shoe so that as the shoe is forced through the water the blades will open and as it is drawn in the opposite direction the blades will close.

20 A further object of the invention is to provide a shoe having a frame in which propeller blades may be inclosed so that the wearer may walk without injuring the blades.

And a still further object of the invention is to provide a simple and inexpensive device that may readily be attached to the feet of a swimmer which is not cumbersome and which will increase the swimmer's propelling power.

30 With these ends in view the invention embodies the upper portion of a shoe having an aluminum frame representing the sole and propeller blades pivotally supported within the said frame.

35 Other features and advantages of the invention will appear from the following description taken in connection with the drawings, wherein:

Figure 1 is a side view of the device.

40 Figure 2 is a sectional plan of the frame with the upper plate removed.

Figure 3 is a cross section through the frame on line 3—3 of Figure 1.

45 Figure 4 is a view looking toward the under side of the device showing the blades in the open position, as they would appear in use.

In the drawings the device is shown as it would be made, wherein numeral 1 indicates the shoe, numeral 2 the frame and numeral 3 50 the blades.

The shoe 1 may be of any suitable type or design and may be made of any suitable material. It is attached to the upper plate 4 of the frame 2 by rivets or screws 5, around 55 the edges as shown in Figure 3. The plate 4

may also be of any suitable design, however it is preferable to have it correspond to the shape of a foot as shown and provided with openings 6 as shown in Figure 3 to reduce the weight. This plate is attached to a lower plate 7 by posts 8 and 9 at the toe and a post 10 at the heel. The propeller blades 11 and 12 are pivotally attached to the post 10, as shown, and each blade is held in the closed position independently by springs 13 and 14 which are attached to the sides of the blades by screws 15 and 16 and to the frame through pins 17 and 18. The plate 7 is provided with a stop 19 which will engage the side of the blade 12 as the blade reaches the closed position, and the upper plate 4 is provided with a pin 20 which extends downward and will engage the side of the blade 11 when it reaches the closed position as shown in Figure 2. The curvature of the blades is shown in Figure 3 and it will be observed that as the device is moved through the water one blade will move outward in one direction and the other outward in the other direction to the respective positions shown in Figure 4.

75 The under side of the plate 7 may be provided with lugs 21 which may be of any suitable resilient material.

80 It is understood that changes may be made in the construction without departing from the spirit of the invention, one of which changes may be in the design or arrangement of the propelling blades, another may be in the use of a different type of frame for supporting them and still another may be in the location of the pivot point as it is understood that the blades may be pivoted at any suitable point.

85 The construction will be readily understood from the foregoing description. To use the device it may be placed upon the feet as described and it will be observed that as the person using the device pushes his feet backward to propel him the blades will instantly open and provide a greater propelling area and as soon as he starts to draw his feet backwards the blades will instantly close.

90 Having thus fully described the invention what I claim as new and desire to secure by Letters Patent, is:

105 1. In a device of the class described a pair of blades pivotally supported at one end and adaptable to swing outward and to fold with one behind the other, and means for attaching them to the soles of the feet.

2. In a device of the class described a pair of blades pivotally supported at one end and adaptable to swing outward and to fold with one behind the other, and means for attaching the blades to the soles of the feet, said blades being of such a curvature that as they are forced through the water in one direction they will spread outward and as they are drawn through the water in the opposite direction they will return to their normal positions with one behind the other.

3. In a device of the class described, a shoe, a frame attached to the said shoe, blades pivotally mounted in the said frame, said blades being pivotally mounted at their ends and adaptable to swing outward and to move inward with one behind the other, means for resiliently holding the blades in the said

frame and means for limiting the movement of the said blades.

4. In a device of the class described, a shoe, a frame attached to the said shoe, blades pivotally mounted in the said frame, said blades being pivotally mounted at their ends and adaptable to swing outward and to move inward with one behind the other, means for resiliently holding the blades in the said frame and means for limiting the movement of the said blades, said blades being of such a curvature that as they are forced through the water in one direction they will spread outward and as they are drawn through the water in the opposite direction they will return to their normal positions.

In testimony whereof I affix my signature.
KARL OSCAR FREDRICK JACOBSEN.
